Primary Examiner — Kendra Leslie Hamilton*Assistant Examiner* — Amanda Christensen(74) *Attorney, Agent, or Firm* — Eversheds Sutherland (US) LLP(57) **CLAIM**

The ornamental design for a solar panel layout on a vehicle, as shown and described.

DESCRIPTION

FIG. 1 is a top, right, front perspective view of a solar panel layout on a vehicle;

FIG. 2 is a top, right, back perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the solar panel layout on a vehicle and form no part of the claimed design. The broken lines showing a vehicle depict environmental structure that forms no part of the claim.
